PEDESTAL

William C. Walsh, Highland Park, Mich.

Application March 17, 1947, Serial No. 735,153

4 Claims. (Cl. 248—194)

1

This invention relates to pedestals particularly usable for stools, tables, posts and the like.

The primary object of the invention is to provide an inexpensive readily manufactured and easily erected sheet metal pedestal or base particularly usable for stools, tables, posts and the like which employs a veneer or outer finished casing that becomes securely anchored and held as an integral part of the base during assembly and erection and contributes to the strength thereof responsive to being anchored in fixed relationship to the floor or other object to which the pedestal is secured.

Other objects of the invention will become apparent by reference to the following detailed description taken in connection with the accompanying drawing, in which:

Fig. 1. is a side elevational view of a pedestal embodying the invention with portions thereof broken away to show the construction.

Fig. 2 is a horizontal sectional view taken on the line 2—2 of Fig. 1.

Fig. 3 is a fragmentary exploded sectional view showing the collar construction just prior to assembly.

Referring now to the drawing wherein like numerals refer to like and corresponding parts throughout the several views, the illustrative embodiment of the invention disclosed comprises, in general, an inner substantially frusto-conical base 10 having an annular top 11 and a central depending collar 12 into which is welded a post or stanchion 13, an annular collar 14 telescoped over the said post or stanchion 13 and bearing upon the annular top 11 of the said base 10, an outer or finished frusto-conical outer casing 15 having an annular inturned upper depending lip 16 pressed in anchored relationship over the said annular collar 14 and wedged in anchored relationship between the said annular collar 14 and stanchion 13. A domed base plate 17 around the outer periphery of which the lower periphery of the said frusto-conical base 10 and the said frusto-conical outer casing 15 are positioned and the lower periphery of the said outer casing 15 is turned under, and means such as a bolt 18, washer 19 and nut 20 for anchoring the said base plate to a floor or the like 21.

The said inner substantially frusto-conical base 10 is preferably formed of either hot or cold rolled steel by drawing, piercing and extruding or like operations to produce a substantially frusto-conical side and an annular top 11 and a centrally depending collar 12 with an inturned annular lower lip 120. The stanchion 13 is pressed into

the collar 12 of the inner base 10 in abutment against the lower annular inturned lip 120 where it is anchored by welding as indicated by the numeral 22 in Figs. 1 and 3.

5 An annular collar 14 preferably of die cast material is then pressed over the stanchion 13 until the bottom thereof is in contact with the annular top 11 of the inner substantially frusto-conical base 10. The upper inner periphery of 10 the annular collar 14 is formed slightly inwardly tapered and larger in diameter than the stanchion 13 at 23 and is annularly chamfered at 24 and 25 as best illustrated in Fig. 3 to permit the annular inturned upper depending lip 16 of the outer casing 15 to be pressed in sealed relationship into the top of the annular collar 14 between the said collar 14 and the stanchion 13 as shown in Fig. 1.

15 The said outer finished casing 15 is formed to conform with the contour of the inner substantially frusto-conical base 10 and annular collar 14 when pressed thereover, the lower annular periphery 150 of the said outer finished casing 15 depending below the lower periphery of the inner base 10 as indicated by the dot and dash lines in 20 Fig. 1. The domed base plate 17 having a substantially horizontally disposed periphery 170 is then placed within the lower peripheral rim 100 of the inner substantially frusto-conical base 10 and the said lower annular periphery 150 of the said outer casing 15 is bent inwardly under the said substantially horizontally disposed periphery 170 of the domed base plate 17. The said domed base plate 17 is preferably provided with a plurality of apertures 26 and radial cuts 27 to permit it to 25 flex and expand slightly when it is drawn tightly against the floor or the like 21 during installation of the pedestal by turning the nut 20 onto the bolt 18 by means of an elongated wrench (not shown) which is extended down through the center of the stanchion 13.

30 The securing of the pedestal tightly to the floor or the like anchors the periphery 150 of the outer finished casing 15 under the horizontally disposed annular periphery of the base plate 17 and secures the inner base 10, the stanchion 13, the annular collar 14, the finished casing 15 and base 17 into a rigid unitary whole. With standard parts throughout, the outer finished casing may be of 35 any desired material or finish whereby to accommodate pedestals constructed in accordance with the invention to any desired design and color scheme such as stainless steel, enamel, bronze or the like with a minimum of expense.

40 Although but a single embodiment of the invention has been disclosed and described in de-

tail, it is obvious that many changes may be made in the size, shape, arrangement and detail of the various elements of the invention without departing from the spirit and scope thereof as defined by the appended claims.

I claim:

1. A pedestal comprising an inner substantially frusto-conical base, a stanchion fixed centrally therein and extending thereabove, a collar disposed around said stanchion bearing against the top of the said frusto-conical base, an outer finished frusto-conical casing having an upper annular inturned depending lip wedged in anchored relationship between the inner periphery of the said collar and the said stanchion, the lower peripheries of the said inner frusto-conical base and the outer finished frusto-conical casing having inwardly turned over-lapping peripheries, and means engaging the said over-lapping peripheries for anchoring the said pedestal to a floor or like structure whereupon the entire pedestal components become secured into a rigid unitary whole.

2. A pedestal comprising an inner substantially frusto-conical base, a stanchion fixed centrally therein and extending thereabove, a collar disposed around said stanchion bearing against the top of the said frusto-conical base having the inner periphery of the top thereof formed slightly inwardly tapered and larger than the said stanchion providing an annular wedge recess around the top of the said collar adjacent the said stanchion, an outer finished frusto-conical casing having an upper annular inturned depending lip wedged in anchored relationship between the inner periphery of the said collar and the said stanchion, the lower peripheries of the said inner frusto-conical base and the outer finished frusto-conical casing having inwardly turned over-lapping peripheries, and means engaging the said over-lapping peripheries for anchoring the said pedestal to a floor or like structure whereupon the entire pedestal components become secured into a rigid unitary whole.

3. A pedestal comprising an inner substantially frusto-conical base, a stanchion fixed centrally therein and extending thereabove, a collar disposed around said stanchion bearing against the top of the said frusto-conical base, an outer finished frusto-conical casing having an upper annular inturned depending lip wedged in anchored relationship between the inner periphery of the said collar and the said stanchion, a domed base

plate having a substantially horizontally disposed periphery placed within the lower annular peripheral rim of the inner frusto-conical base, the lower annular periphery of the said outer casing being formed under the said substantially horizontal periphery of the said domed base plate, and means engaging the central portion of the said domed base plate for anchoring the said pedestal to a floor or like structure whereupon the inner base, the stanchion, the annular collar, the finished casing and the domed base plate become secured into a rigid unitary whole.

4. A pedestal comprising an inner substantially frusto-conical base, a stanchion fixed centrally therein and extending thereabove, a collar disposed around said stanchion bearing against the top of the said frusto-conical base having the inner periphery of the top thereof formed slightly inwardly tapered and larger than the said stanchion providing an annular wedge recess around the top of the said collar adjacent the said stanchion, an outer finished frusto-conical casing having an upper annular inturned depending lip wedged in anchored relationship between the inner periphery of the said collar and the said stanchion, an apertured domed base plate having a radially slotted and substantially horizontally disposed periphery placed within the lower annular peripheral rim of the inner frusto-conical base, the said apertures in the domed base being disposed radially inward of and spaced between the said slots therein, the lower annular periphery of the said outer casing being formed under the said substantially horizontal periphery of the said domed base plate, and means engaging the central portion of the said domed base plate for anchoring the said pedestal to a floor or like structure whereupon the inner base, the stanchion, the annular collar, the finished casing and the domed base plate become secured into a rigid unitary whole.
